VAPORIZER FOR DEODORANT AND SIMILAR TABLETS

Charles C. Diehl, 904 Ruth St., Belmont, Calif.

Filed Dec. 7, 1959, Ser. No. 58,573

Term of patent 7 years

(Cl. D16—2)

Fig. 1 is a side elevational view of a vaporizer for deodorant and similar tablets showing my new design, both sides thereof being identical.

Fig. 2 is a front elevational view thereof.

Fig. 3 is a rear elevational view thereof.

Fig. 4 is a perspective view thereof taken from the right side and above, and on a slightly reduced scale.

Fig. 5 is an elevational view showing one end thereof.

Fig. 6 is an elevational view showing the opposite end thereof.

I claim:

The ornamental design for a vaporizer for deodorant and similar tablets, as shown and described.
